UNITED STATES PATENT OFFICE.

FRANK W. COLLINS, OF CORTLAND, NEW YORK.

DESIGN FOR A STOVE.

SPECIFICATION forming part of Design No. 23,584, dated August 21, 1894.

Application filed June 12, 1893. Serial No. 480,319. Term of patent 7 years.

To all whom it may concern:

Be it known that I, FRANK W. COLLINS, a citizen of the United States, and a resident of Cortland, in the county of Cortland and State 5 of New York, have invented a certain new and useful Design for Heating and Ventilating Stoves, of which the following is a specification, reference being also had to the accompanying photograph, fully representing 10 the same.

The leading features of my design consist of the following:—

First. A nickel plated cover A, oval in form and rising from casting below in form 15 of a dome, worked in raised and polished scroll work, with similarly raised and polished nickel plated edge, supporting said scroll work. The portions of said lid between the raised and polished scroll work and polished work of the edge being nickel plated and unpolished. All as shown in drawing.

Second. A nickel plated and polished section or top B, of open or perforated scroll work, beneath the cover A, and covering and 25 substantially concealing from view the magazine of the stove, harmonizing in its outlines and ornamentations with the cover above, forming with it an ornamental top to the stove. Said perforated top has a glass jewel, in a 30 nickel rosette, in the center of the front, and on either side a smaller rosette with round tile decorations, and also a rosette in each end inclosing a similar tile. Said top B extends outward and slopes gradually away 35 from said swing cover A, and then curving slightly inward, swells and curves outward beyond its first extension, coming down slightly over the four sides of the stove. The polished open work on the four sides of the 40 stove is divided at the corners by a broad band of plain, polished nickel running from the top to the bottom of the section and following its contour, thus forming a panel on each side of the stove. The first extension 45 of the section B is smooth and polished throughout, except that small grooved channels of unpolished nickel radiate outward from the bottom of the cover A nearly to the edge of extension. The base of the section 50 has a broad, polished band of nickel, with unpolished vertical grooves at the corners, and separated from the open scroll work by

a narrow, unpolished band, all as shown in drawing.

Third. Undersaid section B, a band C, showing raised leaves, buds and flowers, extending around the stove,—except a portion of the back,—with narrow, plain, vertical surfaces at the four corners dividing the band. Also a narrow, plain band beneath the band of 60 leaves, buds and flowers. From the base of this band the body of the stove recedes slightly at an angle till it comes into the plane of the doors, and furnishes a rest or stop for the tops thereof. All as shown in 65 drawing.

Fourth. The doors, D, D, D, and E, E, E, the former being the upper and the latter the lower mica doors of the stove. These doors are of peculiar or double design, the foundation skeleton or portion supporting the mica, 70 being in rectangular sections, grooved and studded with half round turnings or projections. Upon this foundation is laid the ornamental or decorative scroll work. The doors 75 are surrounded or edged with transverse bead- ing. All as shown in drawing.

Fifth. Separating the doors on the front of the stove from those on the sides, the four polished nickel corner columns F, F, and G, 80 G, which also partly cover upright panels of leaves, buds and flowers, harmonizing with band C, described above. All as shown in drawing.

Sixth. Separating the doors D, D, D, and E, 85 E, E, and furnishing ornamentation beneath said doors, the two bands H, H, extending around the stove, their ornamentation consisting of over-lapping leaves. All as shown in drawing.

Seventh. A nickelized and polished hood, I, 90 harmonizing with the other nickel work of the stove, covering the ash-pit door, swelling out from top and ends of same, and bearing the words, "Howe Ventilator," and the numbers, "32," "34," or "36," according to size of 95 stove. All as shown in drawing.

Eighth. The polished and nickelized foot rails and brackets J, J, composed of three parts, the brackets and rails perforated, and 100 both brackets and rails ornamented in scroll work to harmonize with other ornamentation of the stove. All as shown in drawing.

Ninth. The ash-pit bottom K, ornamented

at each front upper corner with raised rectangular work, and on the four sides with vertical, raised design, with plain, narrow band above and below. All as shown in photograph.

5 Tenth. The lower bottom L forming a broad, plain band below ash-pit bottom K.

Eleventh. The skirt M, M, and legs N, N, N, with surfaces of polished and nickelized 10 raised work, harmonizing with other ornamental work of the stove, all as shown in drawing.

These leading features all enter into the complete design, substantially as illustrated.

15 The design, ornamentation, or configuration is produced in the main by casting the stove in metal, in manner well known in the art, and by grinding, polishing, plating, and otherwise finishing the castings as is common, 20 so as to produce the ornamentation and configuration substantially as shown and described.

What I claim is—

25 1. In a design for a stove, the upper section B comprising the open scroll work having a rosette in the center of the front and a smaller rosette at each side, and having the inward curve and outward swell, substantially as shown.

30 2. In a design for a stove, the upper door section, comprising the corner columns, and the interposed rectangular panels having rect-

angular cross bars with studded surfaces, and a decorative scroll connecting the cross bars, and the surface ornamentation all as 35 shown and described.

3. In a design for a stove, the fire pot section having the corner columns partly covering rectangular panels which are divided by rectangular cross bars connected by scroll 40 work, the surface ornamentation being substantially as described and shown.

4. In a design for a stove, the ash pit section showing the hood swelling out from the top, bottom, and ends, and having the ornamental scroll work and a name plate substantially as shown and described. 45

5. In a design for a stove, the bottom section beveled as shown and having raised rectangular figures with a plain band above and 50 below, and a swelling skirt M below the lower plain band, the surface ornamentation being substantially as shown and described.

6. The design for a stove comprising the form and surface ornamentation substantially 55 as shown and described.

Signed at Cortland, in the county of Cortland and State of New York, this 16th day of June, A. D. 1893.

FRANK W. COLLINS.
